UNITED STATES PATENT OFFICE

137,440

DESIGN FOR A SCOOP

Milo C. Long, Tiffin, Ohio

Application September 8, 1943, Serial No. 111,075

Term of patent 7 years

To all whom it may concern:

Be it known that I, Milo C. Long, a citizen of the United States, residing at Tiffin, in the county of Seneca and State of Ohio, have invented a new, original, and ornamental Design for a Scoop, of which the following is a specification, reference being had to the accompanying drawing, forming part thereof.

I claim:

The ornamental design for a scoop, as shown.

MILO C. LONG.
